DESIGN FOR A BRACELET OR SIMILAR ARTICLE

William W. Hobé, New York, N. Y.

Application September 10, 1948, Serial No. 148,531

Term of patent 3½ years

(Cl. D45—4)

To all whom it may concern:

Be it known that I, William W. Hobé, a citizen of the United States of America, residing in New York city, county of New York, and State of New York, have invented a new, original, and ornamental Design for a Bracelet or Similar Article, of which the following is a specification, reference being had to the accompanying drawing, forming part thereof, wherein:

Fig. 1 is a front elevational view of a bracelet showing my new design.

Fig. 2 is a side elevational view of the bracelet shown in Figure 1.

The units of the bracelet shown in solid lines are repeated alternately as indicated by the units illustrated in dotted lines.

I claim:

The ornamental design for a bracelet or similar article, substantially as shown and described.

WILLIAM W. HOBÉ.
